UNITED STATES PATENT OFFICE.

JESSE F. HALL, OF GRENO LA, KANSAS.

DESIGN FOR A NUT-LOCK WASHER.

SPECIFICATION forming part of Design No. 32,995, dated July 24, 1900.

Application filed June 28, 1900. Serial No. 21,887. Term of patent 7 years.

To all whom it may concern:

- Be it known that I, JESSE F. HALL, a citizen of the United States, residing at Grenola, in the county of Elk and State of Kansas, have 5 invented and produced a certain new and useful Design for a Nut-Lock Washer; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.
- 15 This invention relates to a new and useful design for a nut-lock washer, of which the following is a specification, reference being had to the accompanying drawings, forming a part thereof.
- 20 The design is clearly illustrated in the drawings, in which I have shown a perspective of the washer in Figure 1. In Fig. 2 I have shown an end elevation, and in Fig. 3 is shown a side view.
- 25 Reference being had to the details of the design, the body portion of the washer is sub-

stantially triangular shape with laterally-disposed wings A, which wings are diagonally disposed at right angles to the face of the body portion, the two bent portions of said 30 wings being at right angles to each other, and a circular outlined aperture is disposed in the body portion of the washer adjacent to the angle formed by the two upturned wings. The portions of the laterally-disposed wings 35 adjacent to the body portion of the washer are flat and coincident with the plane of the washer, while acute angles are formed between the adjacent edges of the body portion of the washer and the wings, as shown clearly 40 in the drawings.

Having thus described my invention, what I claim as new, and desire to secure by Letters Patent, is—

The design for a nut-lock washer, as herein 45 shown and described.

In testimony whereof I affix my signature in presence of two witnesses.

JESSE F. HALL.
